UNITED STATES PATENT OFFICE.

JOHN T. SMITH, OF SAN FRANCISCO, CALIFORNIA.

PILOT LIGHT.

Application filed June 28, 1926. Serial No. 119,127.

This invention relates to improvements in pilot lights and has particular reference to an attachment for use with heating equipment such as flat irons and the like, wherein it is desired to indicate the fact that the current is turned on in the iron.

The principal object of this invention is to produce a device of this character wherein a pilot light may be quickly attached to the plug of a heating device which light will become illuminated as soon as the current is turned on to the heating device.

Another object is to produce a device of this character which is simple in construction, cheap to manufacture and easy to use.

An additional object is to produce a light of this character which will be of small size and, therefore, out of the way.

Other objects and advantages will be apparent during the course of the following description.

In the accompanying drawing forming a part of this specification, and in which like numerals are employed to designate like parts throughout the same,

Figure 1 is a side elevation of an electric plug having my device attached thereto,

Figure 2 is a bottom plan view of the plug cap showing the customary contact prongs,

Figure 3 is a bottom plan view of my device,

Figure 4 is a bottom plan view of my device attached to the plug cap of Figure 2, taken on the line 4—4 of Figure 1, and

Figure 5 is a vertical cross section of my device as it appears attached to the complete plug.

At the present time, it is common to attach the heating cord such as commonly used with flat irons and the like by screwing the plug into the socket, after which the heating device functions. There is no manner, however, of determining whether the iron is receiving the current or not. It often happens that an iron may be left turned on for a long period of time which may either burn out the iron or set fire to the surrounding woodwork. By providing a pilot light, the user may readily observe whether or not the iron is turned on, that is, assuming that an iron is being employed.

In the accompanying drawings wherein for the purpose of illustration is shown a preferred embodiment of my invention, the numeral 5 designates the customary screw base

of an electric plug and the numeral 6 the removable cap therefore.

This cap has connected thereto wires 7 which lead to the heating device being used. These wires are connected to prongs, as 80 8 and 9, which prongs are adapted to enter slots in the base 5 and to make contact therein. The structure thus far described is common to all screw plugs.

My device consists of an insulated shell 65 11 within which is mounted a threaded member 12 which forms a light socket within which a bulb 13 may be placed. An insulated contact 14 is centrally positioned within the screw-threaded member and is connected to 70 a conductor 16.

A similar conductor 17 is electrically connected to the threaded member 12. These conductors are shaped as best illustrated in Figures 3 and 4 and are primarily two flat 75 strips each having an opening therein, as illustrated at 18 and 19, respectively.

These openings 18 and 19 are adapted to permit the prongs 7 and 8 of the cap to pass therethrough as illustrated in Figure 4. 80 After this engagement has been made the cap is inserted in the plug in the customary manner. These conductors 16 and 17 will lie between the cap and the plug, as illustrated in Figure 5, thus holding the receptacle positioned at one side of the plug and ready for the reception of the bulb 13.

It will be readily understood that when the plug 5 is inserted in an electric socket, current flowing to the heating element will 90 also illuminate the bulb 13 through the current flowing from the prong 8 through the conductor 16, to the center contact 14, thence through bulb and back through the screw threaded member 12 to the conductor 17 and 95 to the prong 9.

It will thus be seen that my device accomplishes all of the objects above set forth.

It is to be understood that the form of my invention herewith shown and described 100 is to be taken as a preferred example of the same, and that various changes in the shape, size and arrangement of parts may be resorted to without departing from the spirit of the invention or the scope of the subjoined 105 claims.

Having thus described my invention, I claim:—

1. In combination with a plug comprising a base and a cap, said cap having prongs 110

positioned thereon and adapted to enter said base, a receptacle adapted to be attached to said plug, said receptacle having a pair of parallel spaced conductors secured thereto, 5 said conductors having their free extremities perforated so as to engage the prongs of said cap in such a manner as to lie in a plane at right angles to said prongs and said conductors being positioned between 10 said base and said cap.

2. A receptacle adapted to receive a bulb, said receptacle having a pair of conductors

extending therefrom and at right angles to the axis of said receptacle, said conductors lying parallel with each other in such a 15 manner as to have their surfaces of greatest width in the same plane, each of said conductors having an opening formed in the end thereof for the purpose of permitting said conductors to pass over the prongs of 20 a plug cap in the manner described.

In testimony whereof I affix my signature.

JOHN T. SMITH.
